CLAIM

The ornamental design for opera glasses with watch, as shown and described.

DESCRIPTION

FIG. 1 is a top front perspective view of opera glasses with watch showing my new design;

FIG. 2 is a rear top perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The portions of the opera glasses with watch shown in broken lines form no part of the claimed design.
